UNITED STATES PATENT OFFICE.

RYLAND L. TAFT, OF HARTFORD, CONNECTICUT, ASSIGNOR TO THE HARTFORD RUBBER WORKS CO., A CORPORATION OF CONNECTICUT.

BEAD-TRIMMING MACHINE.

1,270,459.

Specification of Letters Patent. Patented June 25, 1918.

Application filed April 14, 1917. Serial No. 161,982.

To all whom it may concern:

Be it known that I, RYLAND L. TAFT, a citizen of the United States, residing at Hartford, county of Hartford, State of Connecticut, have invented certain new and useful Improvements in Bead-Trimming Machines, of which the following is a full, clear, and exact description.

This invention relates to machines for trimming the edges of beads used in pneumatic tires, to free them from a ragged excess of material known as flash which is formed on the edges during molding of the beads.

An object of the invention is to provide a device which will rapidly and quickly remove the flash from a bead, and which can be changed so as to adapt the device for trimming beads of different sizes.

With the above object in view the invention consists in the novel details of construction and combination of parts herein-after described and claimed, it being understood that various modifications may be resorted to within the scope of the appended claims without sacrificing any of the advantages or departing from the spirit of the invention.

The invention can be easily understood from the following description taken in connection with the accompanying drawing in which—

Figure 1 is a plan view of the machine.

Fig. 2 is a side elevation of the machine.

Fig. 3 is a cross-section view of the machine.

Fig. 4 is a detail view showing a locking device.

Fig. 5 is a detail view of an adjusting device.

Fig. 6 is a detail view of one of the disk cutters and the disk guide.

Referring now to the drawing 10 designates the frame of the machine in general.

Upon a pin 11 at one end of the frame two straight arms 12 are pivoted, and between these an arm 13 of the irregular shape shown in Fig. 2 is also pivoted on the pin. Mounted on the arms 12 are disk cutters 14 which coöperate with a disk shear 15 mounted on the frame below them. Guide rollers 16 for properly locating the bead 17 with respect to and directing the bead through the cutting mechanism are mounted

on the arm 13, one roller being disposed in advance of the cutting mechanism and one in rear thereof. The guide rollers coact with a disk guide 18, located between the cutters 14, in positively maintaining the bead in frictional engagement with the shear 15, which is preferably power driven by the belt 19, so that the bead is fed progressively through the cutting mechanism.

The cutters 14 are adjustable toward and away from each other so that beads of various widths may be trimmed. To accomplish this each cutter is fixedly secured to a hub 20' by means of the bolt 20. The hub is carried by a shell 21 which is turnably mounted in a housing 22 formed in the corresponding arm 12. The shell has screw threads 23 on the outside that engage with corresponding screw threads 24 on the inside of a strap 25 that fits in a slot in the housing. By screwing the shells 21 into or out of the housings the cutters 14 may be moved toward or away from each other. The cutters may be locked in adjusted position against longitudinal movement by tightening thumb screws 26 which cause the straps to bind upon and clamp the shells against displacement.

In order that the cutters may operate effectively the shear 15 should be of the same width as the space between the cutters. Accordingly the shaft 27 of the shear is equipped with a nut 28 and holders 29 to interchangeably receive different shears corresponding in width to the width of the bead to be trimmed.

The disk guide 18, is coaxial with the cutters 14, and is of the same thickness as the shear 15. The guide is grooved to conform to the contour of the particular bead to be trimmed, a different guide being provided for each different size or shape of bead. The guide is provided with an axial opening which receives heads 30 formed on the cutter bolts and projecting axially from the cutters. These heads removably support the guide in place, and by means of the heads the guide unites both cutters 14 for movement as a unit radially relatively to the shear 15, but permits each of the cutters and guide to revolve independently. The heads 30 moreover are adapted to interchangeably receive the various guides provided for beads of different sizes.

To promote the most effective working of the machine, the guide rollers 16 are grooved to conform to the contour of the particular bead being trimmed, a different 5 guide roller being provided for each different size or shape of bead.

For adjusting the cutters and disk guide as a unit radially with respect to the shear the free ends of the arms 12 are supported 10 upon the head of a T-shaped plate 31 which is slotted as shown at 32 to receive a bolt 33 upon which it is movable up and down on the frame 10, and may be locked in any desired position by tightening the bolt. 15 The weight of the arms 12 and parts carried thereby normally cause them to rest upon the head of the plate 31. To lock the arms against upward displacement from any adjusted position, a pair of plugs 34 are 20 slidably fitted in corresponding openings formed in the outwardly projecting wall 31' of the frame, and are caused to frictionally bind against the inner faces of the arms by means of a pin 35 having a wedge shaped portion 36 which fits in wedge shaped recesses 37 in the plugs. The pin may be moved outwardly to set the plugs by means 25 of a nut 38, and upon loosening the nut the pin may be moved inwardly to release the 30 plugs.

In operation the machine is equipped with the guide disk 18, shear 15, and guide rollers 16, of the required size and shape for trimming a particular size and shape of bead. 35 The cutters 14 are then adjusted to accurately coöperate with the shear 15. The bead is fed by hand into the receiving end of the machine through a guide eye 39, then the arm 13 is raised to permit the bead being 40 threaded through the groove in the disk guide 18, whereupon the arm is lowered to cause the guide rollers to bend the bead over and coact with the guide in forcing the bead frictionally against the shear so that 45 it will be driven thereby. The machine is now started, the rotating shear causing the bead to be fed progressively through the machine from which it is directed by a delivery roller 40. During the progress of the 50 bead through the machine, the disk cutter, in conjunction with disk shear, will form a shearing cut simultaneously upon the flash on two edges of the bead and most effectively remove the flash leaving the bead in condition to be subsequently built into the tire. 55

Having described my invention, what I claim and desire to protect by Letters Patent is:

1. In a machine for removing flash from 60 a bead, spaced idler disk cutters, a disk shear coacting with the cutters and having its shearing face extending into the space between the cutters, a disk guide for the bead disposed between the cutters, means connecting the guide and cutters for movement 65

as a unit toward and away from the shear, and means for independently driving the shear.

2. In a machine for removing flash from 70 a bead, spaced idler disk cutters, a disk shear coacting with the cutters and having its shearing face extending into the space between the cutters, a disk guide for the bead disposed between the cutters, means detachably connecting the cutters and the 75 guide together, means for moving the guide and the cutters as a unit relatively to the shear, and means for independently driving the shear.

3. In a machine for removing flash from 80 a bead, spaced disk cutters, a disk shear coacting with the cutters, a disk guide for the bead disposed between the cutters and having an axial opening, and axial projections 85 on the cutters entering said opening and connecting the guide and the cutters for movement as a unit toward and away from the shear.

4. In a machine for removing flash from 90 a bead, spaced idler disk cutters, a disk shear coacting with said cutters and having its shearing face extending into the space between the cutters, a disk guide for the bead disposed between the cutters, means for moving the cutters axially toward and 95 away from each other, means for detachably connecting the cutters and the guide together axially, and means for independently driving the shear.

5. In a machine for removing flash from 100 a bead, spaced idler disk cutters, a disk shear coacting with said cutters and having its shearing face extending into the space between the cutters, a disk guide for the bead disposed between the cutters, guide 105 rollers disposed on opposite sides of the cutters and coacting with the disk guide in causing the bead to frictionally engage the shear, and means for independently rotating the shear to progressively feed the bead. 110

6. In a machine for removing flash from 115 a bead, spaced idler disk cutters, a disk shear coacting with the cutters and having its shearing face extending into the space between the cutters, a disk guide for the bead disposed between the cutters, means for moving the cutters and guide as a unit radially with respect to the shear, means for moving the cutters axially toward and away from each other, and means for independently driving the shear. 120

7. In a machine for removing flash from 125 a bead, spaced idler disk cutters, a disk shear coacting with the cutters and having its shearing face extending into the space between the cutters, pivoted arms to which the cutters are secured, a guide for the bead disposed between the cutters, means for moving said arms on their pivots to adjust the cutters radially with respect to the 130

- shear, means for locking the arms in adjusted position, and means for independently driving the shear.
8. In a machine for removing flash from a bead, spaced idler disk cutters, a disk shear coacting with the cutters and having its shearing face extending into the space between the cutters, a disk guide for the bead disposed between the cutters, means for 5 moving the cutters toward or away from each other to adjust them to the various sizes of bead to be trimmed, means to which said disk guide is secured adapted to interchangeably receive various disk guides 10 corresponding to the various sizes of beads to be trimmed, means to which said shear is secured adapted to interchangeably receive various disk shears corresponding to the various sizes of beads to be trimmed, 15 and means for independently driving the shear.
- 20

9. In a machine for removing flash from a bead, spaced idler disk cutters, a disk shear coacting with said cutters and having its shearing face extending into the space between the cutters, spindles to which the cutters are attached, a shell carrying each spindle and having screw threads on the outside, a housing in which the shell is turnably mounted, a threaded member in the 25 housing engaging the screw threads of the shell, manual screwing of the shells into or out of the housings serving to move the cutters toward or away from each other axially, means for causing the threaded members to 30 bind upon and clamp the shells in adjusted positions, and means for independently driving the shear.

Signed at Hartford, Conn., this 11th day of April, 1917.

RYLAND L. TAFT.
